UNITED STATES PATENT OFFICE

155,575

DESIGN FOR A COMPASS DIAL

Vernon E. Budlong, Brainerd, Minn.

Application December 5, 1947, Serial No. 142,961

Term of patent 14 years

(Cl. D52—1)

To all whom it may concern:

Be it known that I, Vernon E. Budlong, a citizen of the United States of America, residing at Brainerd, in the county of Crow Wing, and State of Minnesota, have invented a new, original, and ornamental Design for a Compass Dial, of which the following is a specification, reference being had to the accompanying drawing forming a part thereof wherein:

Figure 1 is a plan view of a compass dial, showing my new design.

Figure 2 is an edge view thereof.

I claim:

The ornamental design for a compass dial, as shown.

VERNON E. BUDLONG.
